COMMUNICATION SYSTEM

Walter S. Lemmon, New York, N. Y., assignor, by
mesne assignments, to International Business
Machines Corporation, New York, N. Y., a cor-
poration of New York

REISSUED

Application February 15, 1934, Serial No. 711,313

9 Claims. (Cl. 178—53)

This invention relates to communication systems employing synchronous, in-phase operation of a transmitter and a receiver, and applies particularly to a system wherein the intelligence is conveyed by electrical impulses identified by their timing with reference to an arbitrary time scale.

For such a system it is desirable that the sender include a rotary signal impulse collector which is operated at uniform speed and that the receiver include a rotary signal distributor which is operated at the same speed.

In accordance with the present invention, correspondence between the speeds of the sending collector and the receiving distributor is secured by causing an operating impulse to be transmitted by the sender at a predetermined point in each cycle of the sending collector, and by providing in the receiver a frequency responsive operating motor for the distributor which is adapted to be operated at the same speed as the sending collector by energy supplied at the frequency of the received operating impulses.

It is a feature of the invention that the operating impulses and the signal impulses which are received together after phase correspondence has been established are separated and distinguished by the receiver so that the signal impulses are not permitted to affect the distributor operating means.

It is a further feature of the invention that provision is made in the receiver of frequency multiplying means and of distributor operating means responsive to the multiplied frequency of the operating impulses to operate the receiving distributor at the same speed as the sending collector.

Other objects and advantages will herein-after appear.

40 In the drawing forming part of this specification,

Figure 1 is a diagrammatic view illustrating the sending and receiving apparatus; and

45 Figure 2 is a fragmentary diagrammatic view illustrating another form of apparatus embodying features of the invention.

The sender comprises a commutator ring 1 which includes an operating-impulse contact 2 and a multiplicity of signal contacts 3 of which only a few are illustrated. The operating-impulse contact is connected through a conductor 4 to a battery 5, thence through a conductor 6 to a suitable transmitting or broadcasting means indicated by the rectangle 7. The transmitting means 7 is connected by con-

ductor 8 with the hub portion of a sending collector 9. The battery 5 is effective to produce an impulse through the transmitting means 7 each time that the collector arm 9 wipes across the contact 2. The collector arm 9 rotates at uniform speed and hence the operating impulses are sent out at uniform time intervals.

Between successive operating impulses the collector arm 9 wipes across all of the signal contacts 3 in predetermined order completing a circuit through the transmitter 7 as it touches each contact. The contacts 3 are adapted to be selectively charged by means not shown, and any such contact that is charged will cause an impulse to be sent out as the collector arm 9 15 wipes across it. Such an impulse will obviously be timed with reference to the operating impulse, in accordance with the position of the particular character contact which is charged. These character contacts are so disposed around 20 the circumference of the collector that they are separated from the operating-impulse contact 2 by a time distance greater than the length of the operating-impulse.

The sender may be used in line telegraphy or 25 carrier current systems, or for radio. A radio antenna 10 is indicated.

In the receiver, an antenna 11 is connected to an amplifier 12 and this amplifier is connected through a conductor 13 to a battery 14. The 30 battery 14 is in turn connected through a conductor 15 with the hub portion of a rotary distributor arm 16. The distributor arm 16 carries two brushes which are electrically connected to one another. One of these brushes is 35 adapted to wipe across contacts 26 which are mounted on a stationary disc 27 and which correspond in their positions with the signal contacts 3 of the sender. The other brush forms part of a device 17 which closes a circuit between 40 conductor 15 and either a ring segment 22 or contacts 23, 24 and 25.

The ring segment 22 and the contacts 23, 24 and 25 are the same as the correspondingly numbered parts disclosed in my pending application, Serial No. 684,362, filed August 19, 1933, for Synchronizing system. In said application disclosure is made of the idea of utilizing what are referred to herein as the operating impulses, for adjusting the receiving distributor into phase 50 correspondence with the sending distributor. In the present apparatus they may serve the same purpose, but they are additionally utilized (amplified) to actually drive the distributor arm 16. The ring segment 22 and the contacts 23, 24 55

and 25, together with the circuits thereof, constitute in said application a means for adjusting the arm 16 a step forward with relation to the sending collector, each time that an operating impulse comes through on the ring segment 22 or the contact 23, and for adjusting the arm 16 a step backward with relation to the sending collector each time that an operating impulse comes through on the contact 25. In normal in-phase operation, the operating impulses come through ordinarily on the contact 24, but may occasionally come through on the contact 23 or contact 25. Such impulses never come through on the ring segment 22 after phase correspondence has once been secured. Signal impulses are not transmitted until the phase correspondence has been secured at which time the ring segment 22 is open circuited to render it inoperative.

In normal operation, the operating impulses are transmitted through a conductor 59, an electromagnet 60, and conductors 63 and 58 to a conductor 70. The conductor 70 is connected to one terminal of an amplifier 11. The other terminal of the amplifier 11 is connected through a conductor 72 to a terminal of the amplifier 12 to complete the output circuit of the amplifier 12.

The electromagnet 60 normally holds up an armature 33 against the force of a spring. The ring segment 22 is provided with a contact 32 with which the armature 33 is adapted to engage when released by the electromagnet 60. When the apparatus is first set into operation, and before any letter impulses have been transmitted, the operating impulses may be transmitted through the ring segment 22, contact 32 and armature 33 to a conductor 34. Such current passes thence through an advancing relay A to conductor 70. As soon as in-phase operation is produced, however, the operating impulses are transmitted through contact 24 and electromagnet 60 so that armature 33 is held away from contact 32. This condition is maintained so long as in-phase operation continues, the result being that no impulses transmitted while the arm 16 is in register with the ring segment 22 can get through to conductor 70. When an impulse is transmitted with the arm 16 engaging contact 23, the current travels through advancing relay A, causing in-phase operation to be immediately restored. This single cycle interruption of the normal circuit through 24 is not of sufficient duration to permit armature 33 to move into engagement with contact 32. Similarly, when the operating impulse is transmitted from arm 16 through contact 25, the current passes through a conductor 55, retarding relay R and conductor 58 to conductor 70, causing in-phase operation to be restored while maintaining the ring segment 22 inoperative.

The mechanism just described is effective both to prevent signal impulses from reaching the amplifier 11, and to transmit power operating impulses to said amplifier. Line current is applied to said amplifier from line terminals 73 and 74, and the output circuit 75 of the amplifier is connected through a transformer T with a circuit 76 which includes the field winding 71 of a phonic motor 78. The rotor 79 of this motor is connected through suitable gearing (not shown) to drive the shaft 80 of the distributor arm 16. The characteristics of the motor 78 are such that it is adapted to be responsive to current of the frequency of the operating impulses, and to respond to current of such fre-

quency by driving the shaft 80 at the same rotary speed as that at which the collector arm 9 of the sender is driven.

In the embodiment of Figure 2 the sending apparatus may be as the same as that of Figure 1 and hence has not been illustrated. The receiving apparatus is also the same as that of Figure 1 with the exception of certain features which will be referred to below. The receiver comprises an antenna 11a and an amplifier 12a. The current is transmitted through a conductor 13a and a device 17a, 27a to a conductor 19a which is connected to one terminal of an amplifier and frequency multiplier 11a. Any one of the several types of frequency multipliers well known in the art may be employed, such, for example, as the magnetic doubler type or the vacuum tube type. A conductor 72a connects the opposite terminal of the amplifier and frequency multiplier 11a with the amplifier 12a, completing the output circuit of the amplifier 12a. The frequency multiplier and amplifier 11a, both of which may be of any suitable type well known in the art, are supplied with current from line terminals 13a and 14a, and the output circuit 75a is inductively connected through transformer Ta with a circuit 76a which includes the field winding 71a of a phonic motor 78a. The motor includes a rotor 79a which is connected to drive the shaft 80a upon which the distributor arm (not shown) is mounted. The rotor 79a may be provided as shown in Figure 2 with a larger number of segments than the rotor 19 of Figure 1. The increase in number may correspond to the frequency multiplications effected by the frequency multiplier.

In such case the effect of frequency multiplication is to produce a finer degree of responsiveness to the operating impulses and a smoother application of power. If preferred, however, the frequency multiplication may be utilized to alter in an advantageous manner the gearing employed, or possibly to obviate the need for gearing. This feature of stepping up the frequency is an important feature where more than one impulse per revolution of the sending collector is wanted, since it is desirable to avoid the complications which would be introduced by attempting to transmit from the sender a plurality of operating impulses in a single revolution of the sending collector.

I have described what I believe to be the best embodiments of my invention. I do not wish, however, to be confined to the embodiments shown, but what I desire to cover by Letters 55 Patent is set forth in the appended claims.

I claim:

1. In a system for conveying intelligence by electrical impulses, in combination, a sender comprising a collector operating at uniform speed and a receiver comprising a distributor adapted to operate at substantially the same speed, said system including means in the sender for transmitting a distributor-operating impulse at a predetermined point in each cycle and signal impulses at other times, means in the receiver responsive to the reception of the operating impulses to rotate the distributor at the same speed as the sending collector, and to adjust it into phase correspondence, and means responsive to phase correspondence for discriminating between the operating and signal impulses.

2. In a system for conveying intelligence by electrical impulses, in combination, a sender

- comprising a collector operating at uniform speed and a receiver comprising a distributor adapted to operate at substantially the same speed, said system including means in the 5 sender for transmitting a distributor-operating impulse at a predetermined point in each cycle, means in the receiver responsive to reception of the operating impulses to rotate the distributor at the same speed as the sending collector, 10 means in the receiver for initially transmitting the operating impulses through to the operating means regardless of the phase relation of the sender and the receiver, means for adjusting the receiver into phase correspondence with the sender, and means for thereafter excluding from the 15 operating means impulses transmitted in the interval between successive operating impulses.
3. In a system for conveying intelligence by electrical impulses, in combination, a sender comprising a collector operating at uniform speed and a receiver comprising a distributor adapted to operate at the same speed, said system including means in the sender for transmitting a distributor-operating impulse at a predetermined instant in each cycle and signal impulses at other times, means in the receiver responsive to reception of the operating impulses to rotate the distributor at the same speed as the sending collector and in phase correspondence 25 therewith, and means in the receiver responsive to phase correspondence for excluding from the operating means impulses received between successive operating impulses.
4. In a system for conveying intelligence by electrical impulses, in combination, a sender, and a receiver comprising a rotary distributor adapted for operation at a predetermined uniform speed, said system including means in the sender for transmitting distributor-operating impulses 30 at uniform time intervals, and signal impulses between successive operating impulses, means in the receiver responsive to said operating impulses to operate the distributor, and means in the receiver responsive to phase correspondence 35 of the sender and receiver for preventing signal impulses from affecting the distributor operating means.
5. In a system for conveying intelligence by electrical impulses, in combination, a sender and a receiver, said receiver including a rotary distributor and means for rotating the same, and said sender including means for transmitting distributor-operating impulses at uniform time intervals, and means in the receiver for utilizing the operating impulses both to effect the driving 45 of the receiver distributor and to produce and maintain phase correspondence of the receiver with the sender.
6. In a system for conveying intelligence by electrical impulses, in combination, a sender comprising means for transmitting operating impulses at uniform time intervals and signal 50 impulses at other times, and a receiver comprising a rotary distributor, means for operating the distributor, a source of electrical energy, means controlled by the operating impulses for causing energy from said source to be supplied periodically to the distributor-operating means, and means responsive to phase correspondence of the sender and distributor for discriminating between the signal and operating impulses. 55
7. In a system for conveying intelligence by electrical impulses, in combination, a sender comprising a collector operating at uniform speed and a receiver comprising a distributor adapted to operate at substantially the same speed, means in the sender for transmitting a distributor-operating impulse at a single predetermined point in each cycle, and for sending signal impulses between successive operating impulses, means in the receiver for receiving the operating impulses and multiplying the frequency of the same, 20 means responsive to such multiplied frequency to rotate the distributor at the same speed as the sending collector, and means responsive to phase correspondence of the sender and distributor for discriminating between the signal 25 and operating impulses.
8. In a system for conveying intelligence by electrical impulses, in combination, a sender comprising a collector operating at uniform speed, and a receiver comprising a distributor adapted to operate at the same speed, said system including means in the sender for transmitting distributor operating impulses at uniform time intervals and for sending signal impulses between successive operating impulses, 30 means in the receiver for receiving the operating impulses and multiplying the frequency of the same, means responsive to such multiplied frequency to rotate the receiving distributor at the same speed as the sending collector, and means 40 responsive to phase correspondence of the sender and distributor for discriminating between the signal and operating impulses. 35
9. In a system for conveying intelligence by electrical impulses, in combination, a sender comprising a collector normally operating at substantially uniform speed, and a receiver comprising a distributor adapted to operate in synchronism with the collector, said system including means in the sender for transmitting distributor operating impulses at the same period in each cycle of the collector and signal impulses at other times, means in the receiver responsive to the reception of the operating impulses to cause the distributor to be operated synchronously with the collector even when the speed of the collector varies, and means responsive to phase correspondence of the sender and distributor for discriminating between the signal and operating impulses. 50 55
